CHAISE

Samuel D. Lockshin, Northampton, Mass., assignor to Hampden Specialty Products Corporation, Easthampton,
Mass.

Filed Nov. 29, 1962, Ser. No. 72,648

Term of patent 14 years

(Cl. D15—1)

FIG. 1.

FIG. 1 is a view in perspective of a chaise embodying my new design; and

FIG. 2 is a side elevation thereof.

The paneled back of the chaise is substantially similar in appearance to the front thereof.

I claim:

The ornamental design for a chaise, as shown and described.
